[57] CLAIM

The ornamental design for mounted bracket for holding tanks, as shown and described.

DESCRIPTION

FIG. 1 is a front, top and left side perspective view of a mounted bracket showing my new design;
FIG. 2 is a front elevational view thereof;
FIG. 3 is a top plan view thereof, the bottom plan view being a mirror image;
FIG. 4 is a rear elevational view thereof; and
FIG. 5 is a left side elevational view thereof, the side opposite being a mirror image.
